APPARATUS FOR THE TREATMENT OF THE
URETHRA

William Monahan, Tacoma, Wash.

Application October 2, 1931, Serial No. 567,067

3 Claims. (Cl. 128—227)

This invention relates especially to devices for the treatment of diseases of the urethra, and has for its objects to provide means whereby the medicament, with which the urethra is being treated, may be periodically changed or renewed therein without either removing the apparatus or inserting any additional medicine therein; to provide means for insuring that the medicine reaches a certain distance up the urethra; to provide means to reduce or increase the air pressure within the urethra to change the medicine therein; to provide means for distending or dilating the portion of the urethra being treated, thereby preventing the diseased sides thereof from contacting with other parts and thus spreading the disease, and also stretching the diseased area and therefore permitting a larger medicinal contact therewith; to provide means for adjusting such dilating means thereby enabling a single apparatus to take the place of several devices of slightly different sizes; to provide a means whereby the urethra may be irrigated; to provide an apparatus which may be continuously worn and will provide a continuous treatment of the diseased parts, thereby reducing the time required for treatment; and to provide an apparatus which may be self applied, and which is simple to operate and effective in use.

I attain these and other objects by the apparatus, devices, mechanisms and arrangements illustrated in the accompanying drawings, in which—

Fig. 1 is a vertical section of the simplest form of my apparatus in use; Fig. 2 is a top plan view thereof, drawn to a larger scale; Fig. 3 is a transverse intermediate section thereof; Fig. 4 is a side elevation of the head or cap thereof; Fig. 5 is a longitudinal section of such cap thereof; Fig. 6 is a bottom plan view of the base thereof; Fig. 7 is a side elevation of the base thereof; Fig. 8 is a partial view, similar to Fig. 1, showing a means of adjustably distending the apparatus; Figs. 9 and 10 are side elevation and transverse section of the lower portion of a variation in the apparatus; Figs. 11 and 12 are views similar to Fig. 10, showing variations in the form or shape of the dilator; and Fig. 13 is a view showing the dilator in use as an irrigator.

Similar numerals of reference refer to similar parts throughout the several views.

Heretofore the application of medicament to the inner surface of the urethra has, of necessity, been applied thereto for but a comparatively short time, during the time that the patient could be attended to by the doctor, with the result that,

upon the withdrawal of the instrument used to dilate the urethra, its sides contract again and come into close contact and the effect of the medicine, which is no longer present to any great extent, is soon lost and the disease continues to advance by such contact.

In this invention I attach the dilator to the penis, thus holding it in place in the urethra, and surround the penis with a liquid-tight bag or chamber, similar to a small urinal, containing the medicine, and conduct the air in the urethra away from a point above the infected part by means of an air pipe, forming part of the dilator, thus causing the medicine to enter and continuously bathe the diseased internal surface of the urethra. Such apparatus may be worn substantially continuously by the patient, the bag alone being removed for urination, and thus keeps the urethra constantly dilated and in contact with its medicine. Further, by attaching a small bulb to the air pipe, above referred to, and contracting said bulb, the pressure of the air in the urethra, above the medicine, causes all the medicine to be driven out into the bag and then, on the release of the bulb, the air pressure is reduced and new medicine is returned from the bag into the urethra, thus permitting the patient to, himself, periodically renew the medicine acting on the diseased parts and greatly enhancing the effect of the medicine on the diseased part. Further, my device may be self applied, after proper instruction, and the patient may periodically renew the medicine in the bag, as required, and continue the treatment, day and night, with but occasional inspection by the doctor. Further, in some forms of my invention, the dilator is adjustable, thus permitting a single instrument to take the place of several of different sizes. In the drawings, I have shown the simplest form of my invention, together with several variations thereof.

Referring to the drawings, it will be seen that my apparatus comprises an outer bag 1 adapted to contain the supply of medicine. This bag 1 is strapped to the body of the patient, with the penis therein, and is similar in form to a small urinal. The bag 1 may be made of rubber or any other suitable material. A small flexible tube 2, preferably of rubber, passes into the bag 1, either through its surface, as shown, or through its orifice. The outer end of this rubber tube 2 may be open near the bag 1, or it may be continued to any convenient place and may have a small rubber bulb 3 attached to its outer end. The inner end of this rubber tube 2 is attached, within the

bag 1, to the end of the central pipe of my dilator, as hereinafter described.

The dilator comprises a cap or head 4, adapted to be thrust into the urethra, beyond the diseased area, and which may conveniently be constructed of suitable metal, or other substance, and which may be fenestrated by suitable openings 5 to permit air connection between the parts of the urethra above and below the said cap 4.

10 The cap 4 forms the upper end of the body of the dilator, which preferably comprises a cage-like construction of four parallel wires 6, leading from the cap 4 to the base. This base may be a suitable spider 7, as shown in Fig. 6, or a perforated plate 8, as shown in Fig. 8, and holds the said wires 6 in separated position as shown.

15 A central pipe 9 extends through the base and upward through the cap 4 and forms the backbone or stiffener for the dilator. The lower end 20 of this pipe 9 is bent at right-angles, as at 10, and is adapted to receive the inner end of the above-described tube 2, thus connecting the air in the upper part of the urethra, above the diseased area, with the outside or with the bulb 3, as described.

25 The body of the dilator may also be made of a tube 11, as shown in Fig. 9, said tube 11 being provided with slots or holes 12 therein to permit the medicine to have easy access to the diseased parts. This tube 11 may be cylindrical in cross-section (Fig. 10), or quadrilateral (Fig. 11), in which case the slots 12 would be in the flat sides thereof, or corrugated (Fig. 12), in which case also the said slots would be at the parts removed

35 from contact with the wall of the urethra.

When the dilator is to be adjustable in diameter, the central tube 9 preferably extends slightly beyond the top of the cap 4 and is not secured thereto but may slide therethrough, without turning. The tube 9 is provided with a screw-threaded enlargement 13 (Fig. 8) where it passes freely through the base of the body of the dilator. A nut 14 is screwed thereon into contact with the said base. The said pipe 9 is connected to the wires 6 forming the body, at points intermediate between the cap and the base, by means of suitable inclined links 15. Thus when the nut 14 draws the pipe 9 down, relatively to the base, then the links 15 act as toggle bars and spread 45 the wires 6 laterally, thus increasing the diameter of the dilator, as desired. Other well known means than the said links 15 may be employed without departing from the spirit of my invention.

55 In Fig. 13 my improved dilator is illustrated in use to cleanse or irrigate the urethra. In this case the dilator is inserted in the urethra, as before, but the bag 1 and tube 2 are omitted and the end of the central pipe 9 of the dilator is connected to an irrigation system comprising a tube 16 leading from the lower end of the pipe 9 to a reservoir 17, containing the cleansing liquid. When the valve 18 in the tube 16 is opened the liquid flows out of the end of the pipe 9 into the upper part of the urethra and thence out through the dilator, thus providing a continuous stream 65 through the passage.

Thus it will be seen that my invention provides a douche for the internal diseased portion of the urethra by permitting the escape of the air from above the said part and thus allowing the surrounding medicine, in which the penis is immersed, to flow upward therein to a point substantially at the same level as in the bag 1. It also permits the said medicine to be ejected from the urethra and fresh medicine to be drawn thereinto, and it also provides a means of irrigating the urethra.

80 It is to be understood that many changes may be made in the details of my invention, as above described, without departing from the spirit thereof as outlined in the appended claims.

85 Having, therefore, described my invention, what I claim, and desire to secure by Letters Patent, is:—

1. An internal urethra bath comprising a portable bag adapted to be strapped on the patient and to enclose the infected member and to contain a liquid medicine; a dilator positioned within said bag and adapted to open the urethra to permit the medicine to enter and bathe its inner surface; a head formed on said dilator and having air passages therethrough; an air pipe extending through said dilator and dilator head; and a flexible tube entering said bag and connected at its inner end to the lower end of said pipe, whereby the air in the urethra, above said dilator, is connected to the outside through the liquid in said bag to permit the medicine to enter the urethra to substantially the same level as in the bag.

95 2. An internal urethra bath comprising a portable bag adapted to be strapped on the patient and to enclose the infected member and to contain a liquid medicine; a dilator positioned within said bag and adapted to open the urethra to permit the medicine to enter and bathe its inner 100 surface; a head formed on said dilator and having air passages therethrough; an air pipe extending through said dilator and dilator head; a flexible tube entering said bag and connected at its inner end to the lower end of said pipe; and 105 a resilient hollow bulb connected to the outer end of said tube, whereby the air pressure in the urethra, above said dilator, may be increased to force out the medicine in the urethra and then decreased to draw in new medicine therein from 110 the bag.

115 3. A urethral dilator comprising a central stiff member; a cap carried by said stiff member; a dilating member surrounding said stiff member and attached to said cap and adapted to provide 120 access of the medicine therein to the inner surface of the urethra; a base member carried by said stiff member and attached to said dilating member; means adapted to adjustably move the dilating member relatively to the stiff member; 125 and means positioned between the cap and the base and connecting said dilating member to said stiff member, whereby when said adjustable means forces said relative movement in one direction the dilating member is expanded in 130 diameter.
